UNITED STATES PATENT OFFICE.

EDWIN L. HENDERSON, OF NORWOOD, OHIO, ASSIGNOR TO THE KEMPER-THOMAS COMPANY, OF NORWOOD, OHIO, A CORPORATION OF NEW JERSEY.

PAPER HAT.

1,239,483.

Specification of Letters Patent. Patented Sept. 11, 1917.

Application filed August 8, 1914. Serial No. 855,734.

To all whom it may concern:

Be it known that I, EDWIN L. HENDERSON, a citizen of the United States, and a resident of Norwood, in the county of Hamilton and State of Ohio, have invented certain new and useful Improvements in Paper Hats, of which the following is a full, clear, and exact description, reference being had to the accompanying drawings, forming part of this specification.

My invention relates to improvements in hats intended to be constructed of paper, and more particularly intended for use in factories and the like, and generally for use in hot weather.

The object of my invention is to provide a hat which shall be light, cool and impervious to moisture, so that it will not be affected by showers of rain, and which shall retain its good shape and appearance under all conditions of weather.

It is also intended, when desired, that advertising matter can be printed on the crown or band.

One difficulty that has been experienced in the manufacture of hats of paper has been to provide a suitable and proper brim, and I have discovered that if the hat is made up of elastic paper and the brim is pressed between hot dies into curved shape in cross section and then applied to the hat band, the proper shape is maintained, and a serviceable and useful hat obtained, without the use of any wire or means other than the ordinary binding for the edge.

In the drawings,

Figure 1 is a perspective view of my improved hat showing the elastic paper used in the construction thereof.

Fig. 2 is a cross section of the same.

Fig. 3 is a cross sectional view showing the method of forming the brim.

In the construction of my improved hat, a sheet of elastic water proof paper is cut to the proper pattern, a circular piece 1 for the crown, a band of the proper length 2 for the band of the hat and an annular band 3 for the brim. This paper must be elastic paper in which preferably the paper

is made up with scorings through the body thereof as shown in Fig. 1. Thus the paper is compressible by flattening out these scorings and elastic by stretching them out.

The crown 1 is sewed to the band 2 in the usual way to form the body of the hat. For forming the brim, I take two annular disks 3, with a similar disk of what is known as Kraft paper for the lining, and press the disk between hot dies 4, 5, into curved shape in cross section. This expands the middle portion of the rings and draws in the edges, and the outer edges are then bound with a binding tape 6, and the inner edges are sewed at 7 to the band of the hat. A sweat band 8, of any suitable material, is then sewed on the inside of the hat, and the hat is then ready for use.

By pressing the brim between hot dies and then binding the outer edges with the tape and securing the inner edges to the hat, the brim maintains its shape. It can be turned down and then up without losing its shape, and acts exactly as the brim of an ordinary soft felt hat.

For the purposes of ventilation, the band 2 can be provided with a series of holes 9, before it is sewed in place.

Having thus described my invention, what I claim as new and desire to secure by Letters Patent, is:—

1. In a paper hat of elastic paper adapted when compressed to retain its compressed shape, the combination with the crown and band, of a brim therefor composed of said paper material compressed into a segmental shape in transverse section and secured to the lower edge of the band, whereby a hat with a permanent curved brim will be provided.

2. In a hat of waterproof elastic paper adapted when compressed to retain its compressed shape, the combination with the crown and band, of a brim therefor composed of an annular disk made up of outer layers of said material, and an inner layer of lining paper, the whole compressed into a segmental shape in transverse section, and having the outer edges bound to maintain the said shape, with the inner edges secured to the lower edge of the band, whereby a hat with a permanent curved brim will be provided.

EDWIN L. HENDERSON.
